UNITED STATES PATENT OFFICE

LOUIS H. HOSBEIN, OF WINNETKA, ILLINOIS, ASSIGNOR TO M. H. DETRICK COMPANY,
OF CHICAGO, ILLINOIS, A CORPORATION OF ILLINOIS

FURNACE CONSTRUCTION

Application filed October 10, 1927. Serial No. 225,186.

This invention relates to furnace construction, particularly to the construction of the furnace chamber. While not limited thereto, it is particularly adapted for embodiment in furnace wall constructions and will be explained by reference to an illustrative embodiment in a furnace wall. It relates to the form of furnace construction in which the furnace closure, such as a wall, is of the air-cooled type, that is, a construction in which provision is made for the circulation of air over the exterior surfaces of the refractories for the purpose of preventing their becoming heated to an undesirably high temperature.

The general object of the invention is the provision of a construction wherein air-circulating lanes may be formed by members which function also to support and hold in place the refractories which form the furnace chamber.

Another object is the provision of a construction which will contribute to rapid dissipation of excessive heat from the furnace refractories, the heat-removing effect being susceptible of control.

Another object is the provision of construction for providing vertical air lanes in a furnace wall structure of the suspended type without substantial increase in cost and without imposing limitations on the flexibility of the wall or facility of repair.

Another object is the provision of a construction for providing vertical air lanes in a furnace wall of the suspended type without involving exposure of the wall-supporting frame members to undesirably high temperatures.

Another object is the provision of a construction for suspended furnace walls with vertical air lanes which involves the use of a minimum number of differently shaped parts.

Yet another object is the provision of such construction which may be easily and quickly installed, and which is susceptible of use in a great variety of furnace chambers.

Other and further objects will be pointed out or indicated hereinafter or will be apparent to one skilled in the art upon an under-

standing of the invention or its employment in practice.

In the accompanying drawings is illustrated furnace wall construction embodying the invention, and certain forms of structural elements employed therein, but it is to be understood that these are all presented simply by way of example, as an aid in explaining the invention, and that they are not to be construed in any fashion such as to limit the appended claims short of the true and more comprehensive scope of the invention in the art.

In said drawings Fig. 1 is a part sectional elevation of a furnace showing the interior elevation of a part of one wall, same having some of the refractories removed to show supporting members, and a conjoining wall in vertical section, which section corresponds to one taken on the line A—A of the figure.

Fig. 2 is another transverse vertical section of the wall structure, as on the line 2—2 of Fig. 1 and

Fig. 3 is a detail in perspective illustrating the form and assembly of certain of the structural elements.

In the examples illustrated in the drawings, the invention is disclosed as embodied in a furnace wall construction of a sectional suspended type such as is described in detail and claimed in the U. S. patent to Raymond D. Foltz, No. 1,747,822. In such a construction the wall is carried on a frame which includes column members 10, ranged along the line of the wall and suitably supported, and transverse members 11 which connect the several columns 10, said transverse members 11 being spaced from one another at appropriate intervals longitudinally of the members 10. The refractory wall, which forms part of the furnace chamber, is made up of a plurality of horizontally running zones, disposed above one another, as herein designated by the reference characters 12, with expansion joints 13 between the zones for accommodating their expansion without subjecting one another to compression. The several zones are in turn made up of sections, each of which comprises a plurality of re-

refractories 14 supported on certain of the transverse members 11 by means of a hanger which retains the refractories in place and spaces their outer ends from the frame members 11 and 10. Upon the frame members 11 are supported the sections 15 of an exterior or sheathing wall which is spaced from the outer surface of the refractory wall to afford an intervening air space.

10 The present invention provides a construction whereby this intervening air space may be subdivided into a plurality of lanes running transversely of the zones 12, through which lanes air may be circulated to carry 15 away heat from the wall refractories and from their supporting hangers, thus to maintain them at safe temperatures. By proper control of the amount of air circulated through the respective lanes, a control may 20 be exercised, within limits, of the temperature of the refractory wall. To this purpose, I provide supporting elements 16 which may be formed most conveniently as iron castings, and which are adapted to support wall 25 sections, as best seen in Fig. 3, each of these supporting elements comprising a body portion 16^a in the form of a plate which is of sufficient width to span the space between the furnace wall and the sheathing wall 15. At 30 its top and outer side the body portion carries a hook 16^b adapted to engage over a flange on a transverse frame member 11, as illustrated in Fig. 1, and at its bottom and inner side the body portion is formed with a 35 foot portion 16^c adapted to bear upon the inner side of a frame member 11. For a part of its length the body portion 16^a is of greater width than the air space, and along the margin of said wider portion is provided 40 with the laterally directed flanges 16^d, which terminate at their lower end at a shelf 16^e. At its top and bottom edges the body portion is provided with the parallel lugs or flanges 16^f which are spaced apart in the 45 direction of the thickness of the plate 16^a. The shelf 16^c is adapted to support a stack of refractories 14 which have anchoring engagement with the flanges 16^d through the 50 medium of T-shaped slots formed in the outer ends of the refractories, said refractories being slid onto the flanges 16^d from the top of the latter. In the assembly of the structure these supporting elements 16 are disposed at appropriate intervals in the length 55 of the wall, being supported on the frame members 11 as above described. The wall sections between those carried on these supporting elements are similarly supported on hangers 17, but which hangers, excepting for 60 their supporting arms 17^a at top and bottom, extend for only a limited distance into the air space between the refractories and sheathing walls. The hangers 17 of a given zone are disposed in staggered relationship to 65 those of superjacent and subjacent zones, so

that the vertical joints between sections are broken. Thus the vertically aligning supporting elements 16 are spaced apart by an intervening zone. These spaces between vertically aligned supporting elements are 70 closed by partition plates 18, which are slid into place edgewise between the flanges 16^f, which flanges retain them at top and bottom against shifting laterally off of the supporting elements. In conjunction with the body 75 portions 16^a of the supporting elements, therefore, these partition plates 18 form continuous vertically running partitions disposed at intervals along the wall and subdividing the air space into vertically running 80 lanes. In Fig. 1 the locations of these partitions are designated by the reference character P. The partition plates 18 preferably are of such width as to extend a short distance into the vertical joint between the sections adjacent them, which sections, as above pointed out, are supported on hangers that are displaced laterally from the supporting elements by the distance of one half a section width. By virtue of this contact of the 85 partition plates with the refractories, as is also the case with the supporting elements 16, heat is transferred from the refractories to these metallic members by conduction, and transferred from them to the contacting air 90 quite rapidly, by virtue of the extensive surface exposure of the plates and supporting elements within the air space.

At top and bottom, the vertical air lanes are in communication, through suitable openings 19 and 20 in the outer wall, with conduits 21 and 22, or other sources of air supply and disposal, so that air may enter at the lower portions of the lanes and flow out at the upper portions, thus maintaining a continuous stream of air passing up across the outer faces of the refractories and about the hangers and along the partition plates and supporting elements 16. This air may be 100 taken from the boiler room, or it may be conducted by the conduit 22 from a pre-heater in the stack, and it may be utilized for supporting combustion in the furnace and for the injection of pulverized or liquid fuel, the heat which it has taken up in its 105 passage through the lanes being thus utilized in the furnace. The air openings 19 and 20 may be controlled by suitable dampers 24 so that the quantity of air passing through the lanes may be regulated, as to obtain a 110 rapid flow for protecting the refractories when the furnace temperature is extremely high, or a reduced flow when the furnace temperature is low and it is not desirable to abstract any substantial amount of heat 115 through the furnace wall. The refractory wall may be carried down, with the construction above described, to the ash pit, or it may be turned off at places as illustrated in Fig. 2 by the use of wedge-shaped refractories 120 125 130 135 140

suspended on suitably formed hangers, to accommodate openings 26 for inspection doors or fuel-feeding devices.

In addition to the control of the air flow, which the invention makes possible as above described, it attains the further important effect of securing full distribution of the air over the entire outer surface of the refractory wall, thus preventing the short-circuiting of the flow in such fashion as to leave dead spaces in which air might stagnate and become heated to a degree detrimental to the refractories or portions of the supporting structure. It will be observed, moreover, that the subdivision of the air space is accomplished in a very simple manner, so far as the structure is concerned, and by use of duplicate and interchangeable elements, as the supporting elements 16 may be of uniform size and pattern and the partition plates 18 limited to only one or two different lengths. The assembly of the structure is a very simple proceeding, as is also the replacement of any of the refractories, hangers or supporting elements in the event repair becomes necessary. The structure has a desirable flexibility so that parts are not subjected to excessive stresses by expansion and contraction of the wall with temperature changes, and the load to which any of the refractories or their supporting members are subjected is maintained below a definite maximum. A further important advantage resides in the fact that the lane-forming partitions do not blanket any of the refractory wall or prevent access of the circulating air to any portion of its area but, to the contrary, effectively contribute to the transfer of heat from the refractories to the temperature-controlling air in the lanes.

What I claim is:

1. In furnace construction, the combination with a sectionally supported wall, of an exterior wall spaced therefrom to afford an intervening air space, supporting elements supporting respective sections of the refractory wall and partition members cooperating with vertically spaced supporting elements to subdivide the air space into separate lanes.

2. In furnace construction, the combination with a supporting frame, of a sectional refractory wall, an exterior wall spaced from the refractory wall to afford an intervening air space, and supporting elements carried by the frame and supporting refractory wall sections, and partition members cooperating with vertically spaced supporting elements to subdivide the air space into parallel separate lanes.

3. In furnace construction, the combination with a supporting frame, of an exterior wall carried on the frame, a sectional refractory wall spaced from the exterior wall and frame to afford an intervening air space,

supporting elements carried on the frame and supporting sections of the refractory wall, and partition members engaged with vertically spaced supporting element and cooperating therewith to subdivide the air space into separate air lanes.

4. In furnace construction, the combination with a supporting frame, of a refractory wall composed of sections one above another, an exterior wall spaced from the refractory wall to afford an intervening air space, supporting elements supporting the refractory wall sections from the frame, and partition members carried by vertically aligned supporting elements and cooperating therewith to subdivide the air space into separate vertical air lanes.

5. In furnace construction, the combination with a frame, of a refractory wall, an exterior wall spaced therefrom to afford an intervening air space, supporting members suspended on the frame and supporting portions of the refractory wall, certain of said supporting members provided with plates extending across the air space between said walls.

6. In furnace construction, the combination with a sectional refractory wall, of an exterior wall spaced therefrom to afford an intervening air space, and supporting members interlocked with and supporting sections of the refractory wall one above another, certain of said supporting members being aligned vertically and provided with plates forming vertical partitions between portions of the air space.

7. In furnace construction, the combination of a refractory wall, an exterior wall spaced therefrom to afford an intervening air space, hangers supporting the refractory wall, and partitions subdividing the air space into separate vertical air lanes, said partitions formed in part by portions of certain of the hangers.

8. In furnace construction, the combination of a frame, an exterior wall, a refractory wall supported by the frame and spaced therefrom and from the exterior wall to afford an intervening air space, and partitions shiftably supported on the frame and subdividing the air space into separate vertical air lanes.

9. In furnace construction, in combination, a refractory wall, an exterior wall spaced therefrom to afford an intervening air space, a frame spaced from the refractory wall, and partition members shiftably supported on the frame and extending into the refractory wall for only a fraction of its thickness and subdividing the air space into air lanes.

10. In furnace construction, in combination, a refractory wall, an exterior wall spaced therefrom to afford an intervening air space, a frame, and metallic partition members supported on the frame and ex-

tending into the refractory wall and subdividing the air space into lanes in which the surfaces of the partition members are exposed.

- 5 11. In furnace construction, in combination, an exterior wall, a refractory wall spaced therefrom to afford an intervening air space, said walls being movable relative to each other for accommodation of expansion, and metallic members extending from the exterior wall into the refractory wall and subdividing the air space into segregated air lanes, said metallic members having areas exposed in the air lanes for cooling effect.
- 10 12. A structure as specified in claim 10 and in which the air lanes are provided with inlets and outlets for air.
13. A structure as specified in claim 8 and 20 in which the air lanes are provided with air inlets and outlets at respective ends.
14. A structure as specified in claim 4 and in which the air lanes are provided with air outlets and inlets at top and bottom.
- 25 15. In furnace construction, a furnace chamber wall and a sheathing wall affording an intervening air chamber, and partition members partially embedded in the furnace chamber wall and subdividing the air chamber into separate air lanes, the exterior surfaces of the furnace chamber wall being entirely exposed in said air lanes.
- 30 16. In a furnace structure, in combination, a sectional furnace chamber wall, a sheathing wall spaced therefrom to afford an air chamber, a frame spaced from the furnace chamber wall, supporting elements whereby the furnace chamber wall sections are supported on the frame, said supporting elements being arranged in horizontal rows at different elevations, and partition members cooperating with supporting elements in different rows to subdivide the air chamber into vertically running air lanes.
- 40 45. In testimony whereof I have hereunto subscribed my name.

LOUIS H. HOSBEIN.
